Primary Examiner — Marianne N Pandozzi(57) **CLAIM**

The ornamental design for a foldable container, as shown and described.

DESCRIPTION

FIG. 1 is a front elevational view of a foldable container showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a top, front and left side perspective view thereof;

FIG. 9 is a top perspective view thereof, showing the foldable container with the cap open;

FIG. 10 is a bottom and front perspective view thereof;

FIG. 11 is a bottom perspective view thereof, showing the foldable container in a folded state; and,

FIG. 12 is a top perspective view thereof, showing the foldable container in a folded state with the cap open.

The broken lines in the drawings illustrate portions of the foldable container which form no part of the claimed design.

1 Claim, 12 Drawing Sheets(56)
